UNITED STATES PATENT OFFICE

JOSEPH A. O'NEILL, OF NEW YORK, N. Y.

BLADE HOLDER

Application filed November 28, 1927. Serial No. 236,220.

This invention relates to blade holders and has for its object to provide a device of the above described class of two part construction possessing strength and durability for holding the well known Gillette and similar razor blades to produce a "knife" for general use where a keen, sharp edge is desirable.

Important features of construction are present in the formation of the parts going to make up the complete article, said parts comprising a handled head having a unitary lock tongue bent outwardly from the body of said head and then upwardly, the last named portion being slightly upwardly and outwardly divergent relative to the plane of said head so that a guard plate may be readily slipped or passed thereover and forced down onto the outwardly bent portion or shank thereof, the guard plate being provided with suitable openings to receive the lock tongue and a pair of outturned lugs for maintaining the razor blade in proper position.

Another feature of the invention resides in the angularity of the handle portion relative to its unitary head, said handle being disposed at a proper obtuse angle to the longitudinal center of said head so that when using the holder, the edge of the blade will be substantially parallel with the face of the object to be cut, thus eliminating to a great extent the possibility of penetrating too far when opening a package and damaging the contents, as for instance, when opening a corrugated paper carton now generally employed for packing purposes.

The angularity of the handle with respect to the head of the device tends to cause the blade to enter the object so that the penetration will be substantially uniform throughout its length, thus reducing to a great extent breakage of blades in use and to further protect the blades I preferably carry the free edges of the head and the guard or clamp plate rather close to the cutting edge of the said blade, leaving but a small portion thereof unprotected against side strains.

The invention possesses other advantageous features which will be set forth in the following description and it will be understood that the configuration and arrangement of the

parts may be varied considerably. The present embodiment illustrates the invention now thought to be the best form but many refinements may be made in the commercial application of the device provided for the purpose set forth.

In the drawings:

Fig. 1 is a side elevation of my improved blade holder.

Fig. 2 is a side elevation of the head part. 60

Fig. 3 is an end view thereof.

Fig. 4 is a face view of the sheet metal blank from which the head part is formed.

Fig. 5 is an end view thereof.

Fig. 6 is an enlarged vertical cross section taken on the line 6—6 of Fig. 1 with slot 28 omitted.

Fig. 7 is a side elevation of a guard plate employed.

Fig. 8 is an end view thereof. 70

Referring to the drawings in detail, the numeral 10 designates the head of the holder with which a handle 11 is formed. These parts or portions are preferably stamped or pressed from sheet metal, the handle being 75 preferably strengthened by turning up a marginal flange 12 which is continued along the head 10 to provide a short end flange or shoulder 13 and a finger ledge 14 on which pressure may be exerted by the thumb or fingers 80 when using the holder, said ledge having a short extension 15 formed with a bead 16 for the purpose hereinafter described.

The head 10 is further formed with a flange or shoulder 17 at the end opposite the shoulder 13 and in carrying out my invention, I stamp a lock tongue 18 and a pair of lugs 19 from the body of said head. The lock tongue is proportioned so that it will pass through the central circular opening in the well known 85 Gillette razor blade 24' and the lugs 19 are positioned to pass outwardly through the usual end openings of said Gillette blade.

The lock tongue 18 is formed with an outwardly directed shank 20 to maintain it in 90 offstanding divergent relation with the plane of the said head to provide a space for blade 24' and a guard or clamp plate 22, see Fig. 6.

The guard plate corresponds to the general shape of the head 10 and is formed with 100

a spring finger piece 23, having a bead 24 to co-act with the bead 16 of the head 10 to lock the parts, the finger piece also being provided with an upstanding terminal lug 25 against which the thumb or finger may be pressed when disengaging the parts 10 and 22.

The guard plate 22 is further provided with an opening 26 and parallel slots 27 to receive the lock tongue 18 and the lugs 19 respectively when the parts are assembled in locked condition.

The extension 15 of the head 10 may, if desired, be formed with a slot 28 to co-act with the bead 24 of the guard plate 22, likewise the finger piece 23 of the guard plate may be formed with a slot 29 to co-act with the bead 16 of the head 10 to lock the parts.

The top edge portions at opposite sides of the finger piece 23 of the guard plate 22 may be turned outwardly as at 30 to avoid the finger ledge 14 of the head when the said guard plate is raised out of engagement with the lock tongue 18 and the free edges of the parts 10 and 22 may be beveled as at 31.

What I claim is:

In a blade holder of the class described, a head having a handle disposed at an obtuse angle thereto, said head also having a finger ledge provided with a beaded portion, end flanges, a lock tongue disposed at an angle to its plane and parallel lugs, a guard plate having a finger piece to engage the finger ledge of the head and openings to receive the said lock tongue and lugs of the head for the purpose set forth.

In testimony whereof, I have signed my name to this specification this 5th day of November, 1927.

JOSEPH A. O'NEILL.
